A.

In possession of
John Bartleby Hugh Christie
George Langford

United States Patent Office.

HUGH CHRISTIE, OF MORRISANIA, ASSIGNOR TO DEBORAH POWERS, ALBERT E. POWERS, AND NATHANIEL B. POWERS, OF LANSINGBURG, NEW YORK.

Design No. 3,479, dated May 11, 1869.

DESIGN FOR A FLOOR OIL-CLOTH, &c.

The Schedule referred to in these Letters Patent and making part of the same.

To all whom it may concern:

Be it known that I, HUGH CHRISTIE, of Morrisania, in the county of Westchester, and State of New York, have invented or produced a new and original Design for Floor Oil-Cloths or other fabrics; and I hereby declare that the same is fully shown upon the drawings accompanying this specification, which I declare to be part of the same; and

What I claim as my invention, and desire to secure by Letters Patent of the United States, is—

The design for floor oil-cloths, or other fabrics, as shown upon the aforesaid drawings.

HUGH CHRISTIE.
